UNITED STATES PATENT OFFICE

LOUIS F. LONG, OF ST. LOUIS, MISSOURI

BOAT-SALVAGING DEVICE

Application filed April 17, 1928. Serial No. 270,760.

This invention relates to salvaging apparatus for use in raising sunken vessels and boats of all characters.

It is well known that when vessels and boats of various kinds sink and settle in mud or sand at the bottom of the water, it is generally difficult and often impossible to pass a cable beneath the bottom of the boat to which it is customary to apply hoisting tackle. Ordinary arrangements provided for lifting such vessels without passing a cable under them are liable to pull out and defeat the object.

A primary object of this invention is to provide simple yet efficient means carried always by the boat and which are built in as a part of the boat, and which, while passing under and around the boat are accessible from the top of the deck, thereby dispensing with all the useless labor of dredging in the mud under the boat in order to get chains or cables under it to raise it, as well as the consumption of time necessary to such a performance.

Another object of the invention is to provide simple and efficient means for forcing air into the various air compartments of the boat to facilitate the raising thereof.

In carrying out these objects, the invention is susceptible of a wide range of modification without departing from the spirit or sacrificing any of the advantages of the claimed invention there being shown in the drawings for illustrative purposes a preferred and practical form in which;

Figure 1 is a perspective view of a boat equipped with this improved apparatus;

Fig. 2 is a side elevation thereof, and

Fig. 3 is a detail perspective view of one of the boat encircling bands constituting a part of the invention.

In the embodiment illustrated, a boat 1 is shown of the closed submarine type, having the usual deck 2.

This boat is provided with a plurality of what we will call salvage bands 3, any desired number of which may be employed, according to the size of the boat in connection with which they are used. These bands 3 are composed of suitable strain re-

sisting metal, of a size and thickness conforming to the size of the boat in connection with which they are to be used. These bands pass under and around the boat at longitudinally spaced intervals and are sunken flush with the boat as is shown clearly in Fig. 1, terminating at their ends on a level with the deck, and provided in said ends with up-standing eye-bolts 4 with which the hoisting tackle may be readily connected. The building in of these salvage bands as a part of the boat avoids all necessity of dredging in mud and water under the boat to get chains under it to raise it and also saves valuable time which is an important factor in the case of a submarine in which the crew is imprisoned. With this form of salvaging apparatus, all that is necessary is for access to the top of the deck to be accomplished and then chains or cables may be secured to the eye-bolts 4 and any power available applied for raising the boat.

To further assist in raising the boat, air pipes 5 are provided, one extending into each air compartment of the boat and projecting at their upper ends above the deck 2 and there equipped with suitable valved connections whereby an air supply hose may be quickly attached thereto so that air may be forced into the compartments, which latter are provided in nearly every form of vessel, and this air, of course, renders the boat more buoyant and more readily raised.

It is, of course, to be understood that any suitable air supply means may be provided for forcing air into the compartments, such as air compression pumps.

Without further description it is thought that the features and advantages of the invention will be readily apparent to those skilled in the art, and it will of course be understood that changes in the form, proportion and minor details of construction may be resorted to, without departing from the spirit of the invention or its scope as claimed.

I claim:

The combination with the hull of a vessel, of a plurality of salvage bands secured

to the exterior of said hull and sunken flush with said exterior, said bands passing transversely around the bottom of the hull and having their ends terminating flush with the deck thereof, said bands being provided at their ends with means for the attachment of hoisting tackle, said means projecting above the deck level to facilitate engagement with the hoisting tackle.

10
